UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

TRANSMITTER.

Application filed October 28, 1922. Serial No. 597,561.

My invention relates to instruments for recording or reproducing sound waves.

One object of my invention is to provide a sound-wave translating device which is characterized by its simplicity of design and operation and which lends itself to inexpensive quantity-production methods of manufacture, the several parts of which may be readily made in existing automatic machinery and may be easily assembled with a minimum expenditure of time and of money.

Another object of my invention is to provide a translating device of the class described, wherein the sound waves are faithfully translated into correspondingly modulated electrical energy without impairing the quality, tone and quantity of the translated energy.

I have found that the above-mentioned desired results may be easily and efficiently accomplished by means of translating device comprising a pair of spaced electrodes between which a glow discharge is formed and providing means for varying the spaced relation of said electrodes in accordance with the varying intensity of sound waves.

The operation of the above-mentioned translating device embodying my invention is based upon the fact that for a given current across the discharge, the voltage drop thereacross varies substantially directly with the length of the discharge. It is to be noted, however, that, if the current through the discharge is allowed to vary, as by employing a supply circuit having a relatively small impedance in comparison with that of the discharge, then the current therethrough varies in an inverse manner with the length of the discharge. Hence, it is seen that such devices may readily effect the translation of sound waves into correspondingly modulated energy, all as explained more fully herein-after.

With these and other objects in view, my invention further consists in the combinations, circuit arrangements and methods of operation hereinafter more fully set forth and claimed, and illustrated in the accompanying drawing, wherein

Figure 1 is a view, partially diagrammatic and partially structural, of a preferred arrangement embodying my invention;

Fig. 2 is a very much enlarged detail view of the discharge electrode shown in Fig. 1;

the above discharge formed therebetween; and

Fig. 3 is a view similar to Fig. 1, but showing a modification.

In Fig. 1 is shown a pair of spaced electrodes 1 and 2, which are connected in series-circuit relation with a stabilizing resistor 3 on the order of a megohm and a source 4 of direct-current energy of about 6,000 volts. The effect of the resistor 3 is to maintain the current substantially constant, notwithstanding slight variations in the impedance of the circuit including the same. The spaced relation between the electrodes 1 and 2 may be varied in accordance with the varying intensity of the sound waves by mounting one of the electrodes, say the positive electrode 1, upon a telephone transmitter diaphragm 5, which is supported upon suitable supporting members 6 and 7.

When the electrodes 1 and 2 are separated by a certain amount, say one-sixteenth of an inch for a system having the constants hereinbefore mentioned, a glow discharge is formed therebetween comprising the following parts arranged respectively between the negative electrode 2 and the positive electrode 1; namely, a cathode glow 8, which is in immediate contact with the negative electrode 2; a cathode dark space 9, sometimes known as Crookes' dark space; a negative light 11; a Faraday dark space 12; and a positive or anode column 13 which terminates on the positive electrode 1, all as indicated on a much enlarged scale in Fig. 2.

As previously stated, it has been observed that, when the length of the glow discharge is varied, as, for instance, by varying the distance between the electrodes 1 and 2, in the manner indicated in the drawing, the potential drop across the electrodes is correspondingly varied. It is believed that the greater part of the potential variation incident to a change in the spacing of the electrodes is caused by changes in the length of the positive column 13, but my invention is not necessarily limited to such theory of operation.

The alternating component of voltage across the electrodes 1 and 2, which is caused by a vibration of the diaphragm 5, may be translated into correspondingly modulated currents by impressing the same through conductors 14 and 15 upon the input electrodes 16 and 17 respectively of a vacuum

tube 18, containing, in addition, an anode or output electrode 19. A stopping condenser 21 may be included in the conductor 14 to prevent the direct-current component 5 of voltage between the electrodes 1 and 2 from being impressed across the input electrodes 16 and 17 of the tube 18. The condenser 21 may be shunted by a grid-leak device 22 to control the value of the negative 10 charge which is built up on the grid 16 during the operation of the tube.

A plate-filament circuit for the tube 18 includes a source 23 of direct-current energy and a coupling coil 24. The amplified modulated currents traversing the plate-filament circuit are impressed upon an outgoing or working circuit 25 through the coupling coil 24 and the coupling coil 26 which is contained in the latter circuit.

20 The arrangement shown in Fig. 3 is distinguished over that shown in Fig. 1 in the provision of a supply circuit which has such low impedance that current variations are produced therein upon the vibration of the 25 electrode 1, rather than potential variations, as in Fig. 1. The supply circuit for the electrodes 1 and 2 now includes a relatively low-voltage source 27 of direct-current energy, and the primary winding 28 of a transformer 29 for translating the current variations in the supply-circuit to amplify the potential variations across the terminals of the secondary winding 31 thereof. The potential variations may be translated into amplified current variations in the manner indicated in the description of Fig. 1. The operation of the modification shown in Fig. 2 is otherwise as indicated in Fig. 1.

As may readily be seen, a glow discharge 40 has certain inherent characteristics in addition to those pointed out in the foregoing portions of this specification which especially fit it for application to sound-wave translating devices in comparison with other forms 45 of discharges, as, for instance, the heated-cathode arc. A few of the desirable characteristics thereof are the attainment of relatively cool electrodes, the substantial elimination of vaporization, melting or burning 50 of electrodes, the elimination of a hot spot, as is found in the ordinary arc, and the steady, smooth and unfluctuating condition of the discharge. The latter is of particular importance, inasmuch as the variations in 55 the intensity or condition of the discharge cause corresponding variations in the potential drop thereacross which, in some cases, may approximate, in magnitude, the potential variations resulting from the diaphragm 60 vibration itself.

While I have shown only two embodiments of my invention and while I have enumerated certain specific values in con-

nection therewith, for the purpose of describing my invention and more fully illustrating the principles thereof, it is apparent that various changes and modifications in the nature, the mode of operation, the constructional details and the specific values referred to may be made without departing 65 from the spirit of my invention. I desire, therefore, that only such limitations shall be imposed thereon as are indicated in the appended claims or demanded by the prior art.

I claim as my invention:

1. A translating device comprising a pair of spaced electrodes in the open air, means for maintaining between said electrodes a discharge of the character which has a dark 80 space and a glowing space and a diaphragm adapted to vibrate in accordance with the varying intensity of disturbing impulses, said diaphragm and one of said electrodes being mechanically connected in such manner that vibration of one is transmitted to the other.

2. In combination, an electrical circuit including a relatively large substantially constant impedance device, a source of energy 90 and a relatively small variable impedance device comprising a pair of spaced electrodes in the open air said source of energy and said constant impedance being so proportioned that the discharge between said electrodes is of the character which has a dark space and a glowing space, means for varying the relative spacing of said electrodes according to a desired frequency, whereby a vibratory electrical quantity is developed in 100 said circuit, and means for translating said vibratory electrical quantity into amplified electrical currents of corresponding vibration frequency.

3. In a sound translating system, a pair 105 of spaced electrodes, means for creating a difference of potential across said electrodes sufficient of itself to render the space therebetween conducting, and sound controlled means for varying the distance between said 110 electrodes.

4. In a sound translating device, a pair of spaced electrodes open to the atmosphere, a circuit including said electrodes, a source of potential high enough to of itself cause a 115 discharge between said electrodes and an impedance greater than the changes of impedance between said electrodes, and sufficient to prevent the discharge between said electrodes from becoming an arc, and means 120 for varying the distance between said electrodes in accordance with the sound.

In testimony whereof, I have hereunto subscribed my name this 25th day of October 1922.

JOSEPH SLEPIAN.
